US00D997364S

(12) **United States Design Patent** (10) **Patent No.:** **US D997,364 S**
(45) **Date of Patent:** **** Aug. 29, 2023**

(54) **PATIENT REPOSITIONING WEDGE**

(71) Applicant: **Medline Industries, LP**, Northfield, IL (US)

(72) Inventors: **Vincent Hahn**, Chicago, IL (US); **Jeremy Fogel**, Evanston, IL (US); **Drew Phalen**, Skokie, IL (US)

(73) Assignee: **Medline Industries, LP**, Northfield, IL (US)

(**) Term: **15 Years**

(21) Appl. No.: **29/757,192**

(22) Filed: **Nov. 4, 2020**

Related U.S. Application Data

(63) Continuation of application No. 29/676,199, filed on Jan. 9, 2019, now Pat. No. Des. 907,777.

(57) **CLAIM**

The ornamental design for a patient repositioning wedge, as shown and described.

DESCRIPTION

FIG. 1 is a top, front perspective view of a patient repositioning wedge in accordance with our new design; FIG. 2 is a bottom, rear perspective view thereof; FIG. 3 is a front elevation view thereof; FIG. 4 is a rear elevation view thereof; FIG. 5 is a top plan view thereof; FIG. 6 is a bottom plan view thereof; FIG. 7 is a right elevation view thereof; and, FIG. 8 is a left elevation view thereof. The broken lines in the drawings depict portions of the patient repositioning wedge that form no part of the claimed design.

1 Claim, 7 Drawing Sheets
